[57] CLAIM

The ornamental design for a gas pressure motor for model airplane, as shown.

DESCRIPTION

FIG. 1 is a side view of the gas pressure motor for model airplane showing my new design;

FIG. 2 is a front view of the gas pressure motor for model airplane;

FIG. 3 is a top plan view of the gas pressure motor for model airplane; and

FIG. 4 is a rear view of the gas pressure motor for model airplane.

Fig. 1.
